UNITED STATES PATENT OFFICE.

JOHN S. BUCKMAN, OF COLLEGE POINT, NEW YORK.

ADJUSTABLE FORM FOR MAKING WIRE HAT-FRAMES.

No. 883,197.

Specification of Letters Patent.

Patented Oct. 16, 1906.

Application filed March 6, 1906. Serial No. 304,496.

To all whom it may concern:

Be it known that I, JOHN S. BUCKMAN, a citizen of the United States, residing at College Point, county of Queens, Long Island, State of New York, have invented certain new and useful Improvements in Adjustable Forms for Making Wire Hat-Frames, of which the following is a specification, reference being had therein to the accompanying drawings, in which—

Figure 1 is a vertical sectional view of the machine; Fig. 2, a detail vertical sectional view of one of the hook-rod clutches; Fig. 3, a plan view of the clutch shown in Fig. 2; Fig. 4, a partial side elevation showing the wire-holding devices released from the wires of the hat-frame; Fig. 5, a detail vertical sectional view of the center post; Fig. 6, a horizontal sectional view taken on the line 6 6 of Fig. 5; Fig. 7, a detail view showing a series of adjustable wire-holding hooks on one of the wire-holding rods; Fig. 8, a plan view of the pattern-holder; Fig. 8^a, a side elevation of the pattern-holder; Fig. 9, a plan view of the machine, showing a hat-frame in position therein; Fig. 10, a detail view of the means for moving the wire-holding devices, and Fig. 11 a section taken on the line XI XI of Fig. 10.

30 This invention has for one of its main objects the production of a device upon which the wire hat-frames for ladies' hats may be made, the construction of the hat-frame being greatly facilitated thereby and its removal when completed being quickly accomplished without distortion of the hat-frame.

A further object of the invention is to provide means whereby hat-frames may be made with decided indentations in the crown or brim portions. In the present method of forming wire hat-frames these indentations are made after the hat-frame is removed from the form on which it is made, the frame being bent inward by the hands of the workmen. It is clear that such bending of the wire frame will not produce hat-frames of uniform shape. By my invention all of said indentations are shaped on the form and require no further manipulation when the hat-frame is removed from the form.

A further object of the invention is to provide means adapted to be operated by either the hand or the foot of the operator, by which all of the wire-holding hooks may be released simultaneously to free the hat-frame and to permit it to be removed from the form, all of

said hooks being then returned to their normal position ready to receive the next hat-frame.

Hat-frames constructed of wire are made up in various regular and irregular shapes with circular, elongated, flat, indented, and straight or bell crowns with brims or coronets having any shape, according to the design.

In this invention the construction is such that the simplest or most complex design can be made without difficulty, and the completed frame may be readily released from its supporting means and removed from the shaping device. So far as I am aware no machine has heretofore been constructed on which hat-frames having indentations, either in the brim or the crown, can be made. To accomplish this, I have found it necessary to reverse the position of the hooks which are to hold the wires at the inner point of the indentation. It will therefore be seen that to release these hooks they must be moved in a direction opposite to the direction of movement of the hooks which receive and hold the wires which form the other parts of the hat-frame. By my invention I provide means for securing this movement of the two sets of wire-holding hooks in opposite directions, thereby making my adjustable form of universal application, with which it is possible to make any and every form of hat-frame and to have all the frames made from one pattern exactly alike in shape.

Other important objects of the invention will appear hereinafter.

Referring to the various parts by numerals, 1 designates a base or support which is adapted to be mounted on a table or bench. 95 Mounted to rotate freely in its support is a base-plate 2, which is formed with a depending tubular socket 3, which turns in a suitable bearing in said support. Secured rigidly to the base-plate and to the socket formed thereon is a central tubular center post 4, which is adapted to rotate with the base-plate. Secured rigidly to the center post a suitable distance above the base-plate is a top plate 5. Connected to this top plate and to the base-plate are a plurality of radially U-shaped arms or supports 6, the upper inner ends of each of said arms being secured to the upper side of the top plate and the lower inner ends of said arms being bolted to the top 110 of the base-plate, as shown clearly in Figs. 1 and 4. The bolts connecting the lower ends

of said arms to the base-plate are axially in line with the screws or other fastening means which secure the upper ends of said arms to the top plate, whereby said supporting-arms 5 may be swung slightly toward one side or the other, as desired. There are usually eight of these supporting-arms employed; but it is manifest that as many of them as may be desired may be used. I have shown the base- 10 plate and the top plate provided with sixteen openings, so that said plates are adapted to support sixteen arms, should it be desired. In Fig. 9 the device is shown as equipped with ten arms. It will of course be understood that each arm carries its supply of wire-engaging hooks.

Mounted in the center post is a vertically-movable bar 7, and secured to this bar near its upper end is a head 8, said head being 20 adapted to slide vertically on the center post and being connected to the slideable bar by means of a pin 9, which passes through a boss on said head and through vertical slots 10, formed in the center post. Connected to the 25 lower end of this bar is an actuating-lever 11, by which said bar may be reciprocated, and to the lower end of said bar is also connected a foot-treadle 12, so that said bar may be moved by the foot of the operator. Between 30 the head 8 and the base-plate is arranged a coil-spring 13, which normally holds the head 8 against the top plate and the bar 7 in its uppermost position.

On the upper horizontal member 6^a of each 35 U-shaped arm 6 are pivoted two pairs of links 14, one pair being mounted near the inner end of said arm and the other near the outer end thereof. These links project an equal distance above and below said arm, one link of 40 each pair being pivoted on each side thereof. Pivotedly connected to said links are two horizontal longitudinally-slotted hook-carrying bars 15, one of said hook-carrying bars being connected to the links above the supporting-arm and the other being connected to the 45 links below the supporting-arm. These hook-carrying bars are substantially equal in length to the supporting-arms, but they may be of any desired length and are slotted practically from end to end. The links in their 50 normal position incline upward and outwardly, as shown in Fig. 1, so that the upper hook-carrying bars are a greater distance from the center post than the lower hook-carrying bars. When the hook-carrying bars are in this position, the lower edges of the 55 upper series rest on the upper edges of the supporting-bars, and the upper edges of the lower series bear against the under side of the 60 supporting-bars. The lower end of one link of each of the inner pairs of links is extended to form the operating-arm 16, said arm being formed with a circular end or ball 17 on its inner free end. All of these circular ends or 65 balls are within the annular channel 18^a,

formed in the head 8. The object of this is to provide means whereby when the center rod is drawn downward the links will be swung on their pivots and the upper hook-carrying bars will be drawn inward toward the center post, and the lower hook-carrying bars will be thrown outward or away from the center post. 70

The hook-carrying bars support the means for holding the wires of which the hat-frame 75 is constructed. These wire-holding devices may be of any suitable form, but I prefer to use rods 18 and to form in the upper ends of said rods hooks 19. These rods are adjustably supported on the hook-carrying bars by 80 means of clamps 20. These clamps consist of a short sleeve 21, inclosing the head 22 of a short stud-bolt 23. The sleeve and the head of the stud-bolt are transversely apertured to receive the rod 18, and the threaded stud 24 85 is adapted to pass through the slot in the hook-carrying bar. By means of the nut 25 the bolt is clamped to the hook-carrying bar. It will be noted that the hook-rod 18 will be bound between the sleeve and the head of the 90 stud-bolt and that the sleeve will be clamped against the hook-carrying bar by the nut 25. By this means the hook-rod may be adjusted along the slot in the hook-carrying bar and may be vertically adjusted through the clamp 95 by the manipulation of a single clamp-nut. Each clutch may be rotated on its said bolt to give the hook-rod any desired inclination. This is important in machines of this kind where it is necessary that the working parts 100 thereof be reduced to a minimum and their manipulation must be as simple as possible.

The hook-rods are variously adjusted and positioned to give the proper positions for the wires which form the hat-frame. In 105 forming an ordinary hat-frame—that is, one without positive indentations in either the brim or the crown parts—the hook-rods are all carried by the upper hook-carrying bars, and all of the hooks face outward—that is, 110 their open ends are turned outward, so that the wires may be readily held in them as they are passed around the device. When, however, it is desired to form a hat-frame having positive indentations in its brim or crown, 115 the hooks to receive the wires at the inner points of the indentations are secured in the lower hook-carrying bar and said hooks are faced inward—that is, their open ends are inward. The reason of this is that to form an indentation in the hat-frame the wires must be carried around on the inner side of the hook. It is manifest that an indentation could not be formed by passing the wire around the outer sides of the hook-rods. 120

It will be manifest that hat-frames of any desired form may be made by means of this device. The most irregular shapes and the most difficult to make can be readily shaped on my device by reason of providing one set 125 130

of wire-holding hooks which face inward and one set which faces outward, so that the wires may be twisted and bent to any desired form and held in that form until properly tied together.

When the hat-frame is completed, it is simply necessary to depress the center bar either by the hand-lever or the foot-treadle, and to thereby slide inward the upper hook-carrying bars to release the hooks carried by said bar from the wires and to simultaneously move the lower hook-carrying bars outward to release the hooks carried by said bars from the wires, and the hat may be lifted clear of the hooks. As soon as the center bar is released the spring raises the head 8 and returns all of the wire-holding hooks to their proper position for forming the next hat-frame.

Whenever it may be necessary to arrange a series of wires vertically one above the other, I prefer to use adjustable hooks 19^a, which may be clamped on the hook-rods, as shown in Fig. 7. By this means it is only necessary to adjust one rod to the proper vertical position and to secure on said rod the adjustable hooks. Without these adjustable hooks it would be necessary to adjust three or more of the hook-rods to bring the three hooks into vertical line one above the other.

A socket is formed in the upper end of the center post to receive the sample-hat holder. As shown in Figs. 8 and 8^a, this holder consists of a center stud 26 and four radial arms 27. These arms are slotted near their outer ends and are provided with adjustable clamps 28, which are adapted to receive the head-size wire of the sample-hat. By this means the sample may be rigidly held in place and the wire-holding hooks be adjusted to their proper positions. It will of course be understood that this sample or model holder is removed with the sample-frame and is not in position when the hat-frame is formed.

During the making of the hat-frame the support is rotated on the base for the convenience of the operator. It will of course be understood that the operating-lever is pivotally connected to a loose sleeve 29, which is clamped between the two rigid collars 30, mounted on the lower end of the center rod. The treadle device is also connected to the center part by a swivel or other suitable means which will permit the center bar to freely rotate. I provide the treadle device so that the operator may release the hat-frame by a foot movement and have his hands free to receive the hat-frame and to remove it from the frame quickly and with care.

It is important that the divergent arms, which support the wire-holding devices, be laterally adjustable on their pivots in order that the wire-holding hooks may be brought

into their proper positions. This I consider a very important feature of my invention. To accomplish this, I provide divergent supporting-arms, as described, and clamp them in their proper positions by means of the 70 bolts passing through the lower ends of said arms and into the base-plate.

Having thus described my invention, what I claim as new, and desire to secure by Letters Patent, is—

75

1. An adjustable form for making wire hat-frames comprising a support, two sets of wire-holding devices, and means for moving one of said sets of devices inward toward the support and the other set of said devices outward away from the support.

2. An adjustable form for making wire hat-frames comprising a support, two sets of wire-holding devices on which the wire hat-frame is formed and means for simultaneously moving one of said sets of wire-holding devices inward and the other set outward to release the wire hat-frame.

3. An adjustable form for making wire hat-frames comprising a support, two sets of wire-holding devices on which the wire hat-frame is formed, means for simultaneously moving one of said sets of wire-holding devices inward and the other set outward to release the wire hat-frame, and means for automatically returning said wire-holding devices to their normal positions to receive the wire for the next hat-frame.

4. An adjustable form for making wire hat-frames comprising a rotatable support, 100 divergent arms carried thereby, slidable bars carried by said arms, adjustable wire-holding devices carried by said bars, and means for simultaneously moving said bars on the arms to release the wire-holding devices from the wires of the hat-frame.

5. An adjustable form for making wire hat-frames comprising a rotatable support, divergent arms carried thereby, movable bars carried by said divergent arms, adjustable wire-holding devices carried by said bars, means for simultaneously moving said bars on the arms to release the wire-holding devices from the wires of the hat-frame, and means for automatically returning said bars to their normal positions, whereby the wire-holding devices will be automatically returned into position to receive the wires for the next hat-frame.

6. An adjustable form for making wire hat-frames comprising a support, two sets of movable divergent bars, wire-supporting devices carried by said bars, means for simultaneously moving one set of bars outward and the other set of bars inward to release the wire-holding devices from the wires of the hat-frame.

7. An adjustable form for making wire hat-frames comprising a support, two sets of movable divergent bars, wire-supporting de-

130

vices carried by said bars, means for simultaneously moving one set of bars outward and the other set of bars inward to release the wire-holding devices from the wires of the 5 hat-frame, and means for automatically returning said bars to their normal positions.

8. An adjustable form for making wire hat-frames comprising a rotatable support, two sets of movable divergent bars, wire- 10 supporting devices carried by said bars, means for simultaneously moving one set of bars outward and the other set of bars inward to release the wire-holding devices from the wires of the hat-frame, and means for automatically returning said bars to their 15 normal positions.

9. An adjustable form for making wire hat-frames comprising a rotatable support mounted upon a center post, two sets of wire- 20 holding devices carried by said support, means carried by the center post and connected to the wire-holding devices whereby one set of said devices may be moved in one direction and the other set moved in the 25 opposite direction.

10. An adjustable form for making wire hat-frames comprising a rotatable support, two sets of horizontally-movable wire-supporting devices, means for moving one of said 30 sets of devices outward and for moving the other set of said devices inward.

11. An adjustable form for making wire hat-frames comprising a rotatable support, two sets of horizontally-movable wire-supporting 35 devices, means for moving one of said sets of devices outward and for moving the other set of said devices inward, and means for automatically returning said wire-holding devices to their normal positions.

12. An adjustable form for making wire hat-frames comprising a support, two sets of movable bars carried by said support, means for moving one of said sets of bars inward and the other set of bars outward and universally- 45 adjustable wire-holding devices carried by the bars of each set.

13. An adjustable form for making wire hat-frames comprising a support, two sets of movable bars carried by said support, means for moving one of said sets of bars inward and the other set of bars outward and universally-adjustable wire-holding devices carried by the bars of each set, and means for simultaneously moving one of said sets of bars inward and the other set outward. 55

14. An adjustable form for making wire hat-frames comprising a support, two sets of substantially radially-movable bars carried by said support, means for moving one of said sets of bars inward and the other set of bars outward and universally-adjustable wire-holding devices carried by the bars of each set, means for simultaneously moving one of said sets of radial bars inward and the 60 other set outward, and means for automatic- 65

ally returning said bars to their normal positions to receive the wires for the next hat-frame.

15. An adjustable form for making wire hat-frames comprising a rotatable support, a 70 series of radial arms carried thereby, two slotted bars carried by each of said arms, wire-holding devices adjustably mounted in each of said slotted bars and means for moving one of said sets of slotted bars inward 75 and the other set outward.

16. An adjustable form for making wire hat-frames comprising a rotatable support, a series of pivoted divergent arms carried thereby, two slotted bars carried by each of said 80 arms, universally-adjustable wire-holding devices carried by each of said slotted bars, and means for moving one of said sets of slotted bars inward and the other set outward. 85

17. An adjustable form for making wire hat-frames comprising a rotatable support, a tubular center post rigidly connected to said support and rotating therewith, a vertically-reciprocable rod mounted in said center post, 90 divergent arms connected to the support, two slotted plates supported by each of said arms, one plate of each pair being above the other below its supporting-arm, a reciprocable head mounted on the center post and connected to the reciprocable rod so as to move therewith, a lever connecting said head to each pair of slotted bars, whereby when said head is moved, the slotted bars will be moved, a spring normally holding the head in its uppermost position, a lever connected to the center bar and adapted to depress said bar, and a series of universally-adjustable hook-rods carried by the radially-movable slotted bars. 95 100 105

18. A wire-holding device for hat-making frames consisting of a sleeve, a stud-bolt having its head inclosed by said sleeve, said sleeve and stud-bolt head being apertured transversely, a wire-holding hook-rod slideable through said aperture and rotatable therein, and a clamping-nut adapted to be screwed on the threaded part of the stud-bolt. 110

19. An adjustable form for making wire 115 hat-frames comprising a support, a series of divergent slotted plates, clamps carried by said plates, each of said clamps consisting of a stud-bolt, a sleeve inclosing the head of said stud-bolt, the sleeve and said head being apertured transversely, a hook-rod carried by each of said clamps, said rod being slideable through said aperture and rotatable therein, whereby each of said hook-rods will be universally adjustable in a vertical plane. 120 125

20. An adjustable form for making wire hat-frames comprising a support, a series of divergent slotted plates, clamps carried by said plates, each of said clamps consisting of a stud-bolt, a sleeve inclosing the head of 130

said stud-bolt, the sleeve and said head being apertured transversely, a hook-rod carried by each of said clamps, said rod being slidable through said aperture and rotatable therein, whereby each of said hook-rods will be universally adjustable in a vertical plane, and a series of adjustable hooks adapted to be secured to the hook-rods.

21. An adjustable form for making wire hat-frames comprising a support, a series of horizontally - movable wire-holding devices

carried by said support, and means for moving a number of said wire-holding devices in one direction and a number of said wire-holding devices in the opposite direction. 15

In testimony whereof I hereunto affix my signature, in the presence of two witnesses, this 26th day of February, 1906.

JOHN S. BUCKMAN.
